UNITED STATES PATENT OFFICE.

ALVIN P. STANDEFER, OF MIAMI, OKLAHOMA.

ORE-CONCENTRATING JIG.

1,333,001.

Specification of Letters Patent.

Patented Mar. 9, 1920.

Application filed October 11, 1918. Serial No. 257,732.

To all whom it may concern:

Be it known that I, ALVIN P. STANDEFER, a citizen of the United States, residing at Miami, in the county of Ottawa and State 5 of Oklahoma, have invented certain new and useful Improvements in Ore-Concentrating Jigs, of which the following is a specification, reference being had to the accompanying drawings.

10 This invention relates to ore concentrating jigs, and particularly to jigs of that character wherein the hutch is provided with a grate or screen upon which the ore is fed and wherein the water in the hutch is 15 caused to surge upward through the grate or screen by means of a reciprocating piston disposed in the piston chamber connected to the hutch.

20 In concentrating jigs of this type as known to me, the hutch is divided into a number of cells disposed in stepped serial relation to each other and the material is carried from one cell to the other.

25 The general object of my invention is to provide an ore concentrating jig of this type wherein each cell is independent of any other cell and the ore does not pass successively from cell to cell, thereby saving fine ore, handling the material better, and cleaning 30 it more perfectly.

A further object is to provide a concentrator comprising a plurality of independent concentrating cells and provide connected chutes whereby the ore may be fed equally 35 to the several cells.

Specifically, my invention consists in providing each cell with a feed box into which the ore is fed directly and from which the ore discharges onto the screen or grate and 40 providing the tail end of each cell with a box receiving the tailings and with a chats separator disposed upon the screen or grate, the feed box for the next adjacent cell being disposed immediately above the tailings receiving box.

45 An embodiment of my invention is illustrated in the accompanying drawings, wherein:—

Figure 1 is a side elevation of a concentrator constructed in accordance with my invention, part of the side wall of the concentrator being broken away;

Fig. 2 is a fragmentary transverse section of the concentrator; and

Fig. 3 is a fragmentary top plan view thereof.

Referring to these drawings, it will be seen that I have provided a series of cells designated A, B, C, etc. The cell A is supposed to be the first cell of the gang or series 60 of cells and is provided with the screen or grate 10, as is usual. Disposed at the head or receiving end of the cell is a feed box 11, which receives the ore in a manner which will be later stated and which discharges 65 the ore and water onto the grate 10 through the spouts 12. Each of the cells A, B and C is formed with a compartment 13, within which operates the usual piston 14, the several pistons being operated by eccentrics or 70 cranks on the usual shaft 15. I do not wish to be limited to any particular means for operating these pistons. The object of the piston is, of course, obvious, that is, to cause the surging of the water in the several cells 75 intermittently upward through the grates so as to lift the material from the grates so that the accompanying parts of the material may arrange themselves on the grates in accordance with their specific gravities. 80

At the discharge end of each cell there is provided the tailings box 16 and above this tailings box there is formed the feed box 11 for the next successive cell. There is a space between the bottom 17 of the feed box and 85 the front wall 18 of the tailings box, this space being sufficiently large to permit a chats separator 19 to be disposed upon the grate 10 and to permit the tailings to pass over the top of the chats separator into the 90 tailings box. This chats separator may be of any suitable character and I have not illustrated it in detail. I prefer to use a chats separator of the character described and illustrated in my prior Patent No. 95 1,162,112, granted November 30, 1915. Each chats separator projects out of the side wall 95 of the cell and the several separators discharge into a trough 20.

At one end of each feed box 11 there is 100 provided an upwardly extending partition 21. This partition is located about 18 inches from the end of the feed box (which feed box is about 9 feet long) and this partition terminates about six inches from the top 105 of the feed box or compartment, so as to provide for lessening the water which is discharged into the feed box and which would be discharged into the coacting cell. This water drains away from the compartment 22 formed by the partition wall 21 110 and discharges through the pipes 23 into a

discharge trough 24. The bottom of each tailings compartment 16 is provided with an outlet spout 25 through which the tailings are discharged into receivers 26 having 5 spouts 27. The bottom of each cell is also provided with a valved spout 28 whereby the contents of the cell may be withdrawn.

For the purpose of discharging mixed ore and water into the several cells of the concentrator, I provide a main chute 29 and provide at intervals hoppers 30 into which the main chute discharges, having a lateral chute 31 extending therefrom and forwardly and rearwardly extending chutes 32 10 which discharge into lateral chutes 33 by means of hoppers 34. The hoppers 30 and the hoppers 34 are provided with waste pipes 35. Each of these lateral chutes discharge into a corresponding feed box 11 at 15 the end thereof opposite the partition 21.

In actual practice the feed boxes are about 9 feet long, 12 inches wide, and a space of about 12 inches is left from the bottom of the feed box to the top of the screen to provide a space for the chats separator and the 20 passage of the tailings over the top of the separator. The concentrator is to be constructed in any usual or suitable manner and any number of cells may be arranged in 25 a battery.

I am aware that it is common in concentrating jigs to use a plurality of cells each provided with a grating and to feed the material successively from one cell to a succeeding cell of the series. In other words, the material is passed over a series of 30 grates and waste material is passed from cell to cell. In these jigs the pulp or other material is all dumped onto the head cell of the series and thereafter passed to each succeeding cell in the series, thereby causing each cell in the series to handle all the waste material that is dumped onto the first cell. In my construction, the contents of the 35 elevator is divided between a plurality of cells as, for instance, six cells and the waste material is taken up from each cell, thereby saving the handling of this waste material five times over and the crowding of any one cell.

In order to properly concentrate ore by means of a cell having a grate through which the water is caused to surge, it is necessary to have an ore or metal bed upon 40 the grate in order to secure the proper concentration. In the ordinary type of concentrator, the greater part of the metal is retained on the grate of the first cell to form the bed thereof, thereby reducing the metal which passes over to the next succeeding cell, thereby reducing the metal bed in each succeeding cell and at the same time reducing the cleaning efficiency of each succeeding cell, until finally the last cells in the 45 series are practically functionless and han-

dle practically nothing but waste material which has been discharged from the preceding cells. In my type, of concentrating jig as heretofore described, each cell performs the same function and by reason of 50 the fact that the contents of the elevator is discharged onto and divided between the six cells instead of one, overloading and overcrowding is done away with and each cell is given a uniform metal bed of its own 55 and is thus enabled to take out practically the entire metal contents of the material.

A further advantage of a concentrator arranged in accordance with this invention over the ordinary concentrator of the same 60 type, lies in the uniform distribution of water to each cell. In the ordinary type of concentrator operating on this principle, the entire water contents used in cleaning the ore is discharged into the first cell and increases in volume as it is passed on to each succeeding cell until at the last cell there is six times as much water as is necessary to properly operate the cell and by reason of this excess water a large amount of the 65 very fine ore is carried off with this excess water into the tailings pile. In my improved concentrator, the water, like the ore, is discharged equally to each of a plurality of cells and each cell discharges its own 70 waste material with its own water and thus the fine ore that is carried away with the excess water in the ordinary concentrator of this type is saved in a concentrator constructed in accordance with this invention, 75 thereby causing a very large saving of this 80 fine ore.

While I have illustrated a specific embodiment of my improved concentrator, it is to be understood that various changes 85 may be made in the details of construction and arrangement of the parts without departing from the spirit of the invention.

I claim:—

1. A concentrator including two cells, 90 there being a wall between the adjacent ends of the cells and extending up the full height of the cells and separating them entirely from each other, a tailings box disposed against said wall at the discharge end 95 of one cell and opening at its upper end into said cell, a feed box disposed immediately above the tailings box above the opening into the cell, the bottom of the feed box forming the top of the tailings box and discharging onto the receiving end 100 of the next cell, and means for discharging ore and water into the feed box.

2. A concentrating jig comprising a plurality of independent cells, each cell having a grate, means for causing the intermittent surging of water through the grate, each cell having at one end a feed box disposed on a level higher than the grate and discharging thereon, each cell at its oppo- 105

site end having a chutes separator, and a tailings box, the body of the cell and the tailings box having discharge spouts, and means for conveying material directly to each feed box, each feed box being provided adjacent one end with an upwardly extending partition less in height than the height of the feed box and providing means for withdrawing surplus water from the feed box.

3. A concentrating jig comprising two cells, each cell having a grate, the discharge end of each cell having a tailings box, into which the tailings from the corresponding

grate discharges and each cell above the tailings box being formed to provide a feed box having spouts discharging onto the next adjacent grate and provided with means for withdrawing surplus water, each cell having means for causing the intermittent surging of water upward through the grate and having means for withdrawing material from the cell and from the tailings box, and means for discharging pulp independently into each feed box.

In testimony whereof I hereunto affix my signature.

ALVIN P. STANDEFER.
